UNITED STATES PATENT OFFICE.

HARRY MARTIN ZIMMERMAN, OF PLUMVILLE, PENNSYLVANIA.

DRAFT ATTACHMENT FOR VEHICLES.

SPECIFICATION forming part of Letters Patent No. 731,411, dated June 16, 1903.

Application filed January 10, 1903. Serial No. 138,454. (No model.)

To all whom it may concern:

Be it known that I, HARRY MARTIN ZIMMERMAN, a citizen of the United States, and a resident of Plumville, in the county of Indiana and State of Pennsylvania, have invented a new and useful Improvement in Draft Attachments for Vehicles, of which the following is a specification.

My invention relates to an improvement in draft attachments for vehicles, and my idea is to obviate the objection to vehicle shafts or thills as now constructed, which resides in a weakness in the swingletree and cross-bar, and particularly in the latter, where all of the strain of draft falls, and in my invention instead of applying the draft to the cross-bar it is applied directly upon the side bars of the shafts or thills or upon the shafts or thills proper, so that no hole is formed in the cross-bar to weaken it and cause it to break.

My invention further consists in certain novel features of construction and combinations of parts, which will be hereinafter described, and pointed out in the claims.

In the accompanying drawings, Figure 1 is a plan view. Fig. 2 is a bottom plan view, and Fig. 3 is a sectional view.

A A represent the side bars of the shafts or thills, and B is the usual cross-bar, connecting them together.

C C are strengthening-plates screwed or bolted to the under side of the shaft or thills for holding them rigidly in place, and these are bent at their rear ends to form couplings 35 1 1, by which they are coupled to the vehicle.

The draft attachment consists of a plate 2, preferably cast from malleable iron and securely screwed or bolted to the shafts at a point preferably at the end of the cross-bar, 40 but not on the latter, there being one of these plates opposite each end of the cross-bar. A hub is formed at the center of each plate, preferably on two diameters 3 and 4, and a turret-plate 5 is counterbored, as at 6 and 7, 45 to correspond with and fit these two hubs.

A bolt 8 passes down through the center of the turret-plate, the inner hub, and the plates C C, and nuts 9 9 on their lower end retain them in position. These turret-plates have 50 hooks 10 10 thereon raised above the surface

of the plates, to which the traces 11 11 are hooked. A connecting-bar 12, pivoted to a lug on each turret-plate, causes them to move in unison.

It will be observed from the foregoing that 55 all strain is removed from the cross-bar to the sides of the shafts, thus preventing weakness at a point where there should be the greatest strength and, on the other hand, applying the draft at the strongest part of the 60 shafts or thills. The hubs and turret-plates are so fitted to each other as to form extended bearing, permitting the turret-plates to turn with perfect freedom and preventing them from rocking laterally upon their bearings. 65 The construction of the turret-plates is such that dirt and other extraneous material are excluded from the bearing, the turret-plate forming a cap therefor. Another advantage of my present construction resides in the fact 70 that the bolts which hold the turret-plates in place extend on through the plates C C, so that the latter sustain a portion of the draft.

I am familiar with certain patents in which the patentees have sought to dispense with 75 the swingletree; but I know of none in which the cross-bar is not utilized to receive the application of the draft. In my invention the cross-bar merely serves the function intended, which is to hold the side bars of the shafts or 80 thills apart as well as connect them; but the application of the draft in my invention is confined to these side bars and is never on the cross-bar.

My improved attachment can be applied to 85 old shafts or thills by simply removing the swingletree, or it may of course be applied to new ones, which is really my intention.

It is evident a simple and inexpensive attachment is provided by my invention which 90 may be easily and quickly applied to either old or new shafts.

Having fully described my invention, what I claim as new, and desire to secure by Letters Patent, is—

1. The combination with a pair of shafts or thills, of plates secured thereto, said plates having concentric hubs of different diameters, turret-plates counterbored to fit these hubs, a bolt for pivotally securing each tur- 100

ret-plate in position and a connecting rod or bar extending from one turret-plate to the other.

2. The combination with a pair of shafts or 5 thills comprising cross and side bars, and two T-shaped plates each made in a single piece, secured to the lower side of the shafts or thills and connecting the cross and side bars together, of turret-plates pivoted on the side 10 bars at the juncture between them and the

cross-bar, and bolts extending through the cross and side bars, and T-shaped plates, to which bolts the turret-plates are pivoted.

In testimony whereof I have signed this specification in the presence of two subscr- 15 ing witnesses.

HARRY MARTIN ZIMMERMAN.
